DESIGN FOR A BROOCH OR SIMILAR ARTICLE OF JEWELRY

Mario Tanzi, Chicago, Ill.

Application May 22, 1944, Serial No. 113,712

Term of patent 14 years

(Cl. D45—19)

To all whom it may concern:

Be it known that I, Mario Tanzi, a citizen of the United States and a resident of Chicago, county of Cook, and State of Illinois, have invented a new, original, and ornamental Design for a Brooch or Similar Article of Jewelry, of which the following is a specification, reference being had to the accompanying drawing forming part thereof.

In the drawing:

or similar article of jewelry, showing my design.

The dominant features of the design reside in the portions shown in full lines.

I claim:

The ornamental design for a brooch or similar article of jewelry, substantially as shown and described.

MARIO TANZI.
